GAS RANGE TOP GRATE AND BURNER

Harry L. Warren, South Pasadena, Calif., assignor to Southern California Gas Company, Los Angeles, Calif., a corporation of California

Application August 5, 1944, Serial No. 548,253

7 Claims. (Cl. 126—214)

1

My invention relates to gas range top grates and burners, and among the objects of my invention are:

First, to provide a gas range top grate and burner which gives improved heat distribution and operates with greater efficiency than conventional burners.

Second, to provide a gas range top grate and burner wherein the grate is in the form of a smooth flat unperforated plate which is particularly easy to clean, and which protects the burner ports from liquid which may be spilled on the range during cooking.

Third, to provide a gas range top grate and burner which affords adequate support for both large and small utensils to minimize the possibility of spilling.

Fourth, to provide a burner and top grate which is so arranged that the burner flame does not come in direct contact with the bottom or side walls of the utensils.

With the above and other objects in view as may appear hereinafter, reference is directed to the accompanying drawings, in which

Fig. 1 is a plan view of a gas range incorporating my top grate and burners.

Fig. 2 is an enlarged fragmentary sectional view thereof, taken through 2—2 of Fig. 1.

Fig. 3 is a plan view of my top grate adapted to an otherwise conventional burner, with a portion of the top grate broken away to show the burner thereunder.

Fig. 4 is a sectional view of the top grate and burner, taken through 4—4 of Fig. 3.

Fig. 5 is a bottom view of the top grate.

My top grate and burner may be adapted to various types and styles of gas ranges. For convenience the gas range 1 itself is represented more or less diagrammatically. The gas range includes a top plate 2 having a suitable burner opening 3 therein. Within each burner opening is a main burner 4 which includes an annular head 5. The head 5 is hollow and defines a mixing chamber 6. The upper annular end of the head 5 is provided with upwardly and outwardly directed burner ports 7. One or more vertically disposed Venturi tubes 8 communicate with the lower annular end of the head 5. At the lower end of each Venturi tube is formed an air chamber 9 in which is positioned as gas nozzle 10. The air chamber 9 is provided with air intake ports 11, the areas of which may be adjusted to regulate the primary air supply by suitable means such as an air valve 12 in the form of a ported cylindrical sleeve surrounding the air chamber 9. 55

2

Within the space formed by the main burner 4 is positioned a simmer burner 13. The upper end of the simmer burner in this modification supports a top grate 14 in the form of a flat plate of uniform thickness except for a central threaded stem 15 which screw-threads into the upper end of the simmer burner 13. The simmer burner defines with the stem 15 a mixing chamber 16 having laterally directed ports 17 located above the head 5 of the main burner 4. The simmer burner 13 includes a Venturi section 18, similar to the Venturi tubes 8.

At the lower end of the Venturi section 18 is an air chamber 19 into which extends a gas nozzle 20. Air intake ports 21 are provided in the side walls of the air chamber 19 and the areas of the intake ports 21 are regulated by an air valve 22, similar to the air valve 12.

It is preferred that the top plate 2 of the range be provided with an upturned rounded rim 23 around each opening 3. An annular burner guard 24 is provided with a curved outer flange 25 which fits over the rim 23, as shown best in Fig. 2. Each burner guard 24 curves downwardly and inwardly from its outer flange and terminates in an annular gutter channel 26 located below the burner ports 7 and radially within the periphery of the top grate 14. The top grate is set above the burner guard 24, to provide an annular clearance space 27.

The top grate 14 provides a smooth flat easily cleaned surface upon which to set cooking vessels. The grate is large enough to support the larger vessels and provide full support for the smaller vessels. By reason of the fact that the top grate extends radially, a considerable distance beyond the burner ports 7, no flame comes into direct contact with the utensils, whether large or small. The hereinbefore described structure eliminates one of the difficulties inherent in the standard type of gas burners; namely, the problem of heat distribution at low burner input while avoiding concentration of heat at the center of the utensil. If in the conventional type of burner a simmer burner is incorporated, low burner heat input is possible but the heat is concentrated at the center of the utensil. If the simmer burner is omitted and the main burner is employed, it will be difficult to turn it low enough to function for simmering purposes without danger of blowout; in any event the burner input is higher than desirable. Tests have shown that the heat distribution by operation of the simmer burner

alone is evenly distributed over the surface of the top grate illustrated.

Both iron and brass plates have been employed to form the top grate 14 and both provide an evenly distributed heat pattern over the entire surface.

Reference is now directed to the construction shown in Figs. 3, 4 and 5. The burner structure per se herein illustrated may be considered as conventional. That is, I have found it possible to add a top grate to a conventional burner of at least one particular style and accomplish results which were comparable to those obtained by means of the first described structure. The burner indicated generally by 31 is commercially available. It comprises a main conduit 32 which has two passages therein, one terminating in an upturned simmer branch 33; and a simmer burner 34 is mounted at the extremity of the simmer branch 33.

A main burner branch 35, which may be separated from the conduit 32, but which extends upwardly from the other passage contained in the conduit 32 and terminates in a ring chamber 36 disposed concentrically with respect to the simmer burner 34. The ring chamber 36 is open at its upper end and is adapted to be closed by a cover plate 37 having a hollow stem 38 which is externally threaded for connection with an internally threaded wall of the ring chamber 36.

The outer periphery of the cover plate 37 at its underside forms with the corresponding side of the ring chamber 36 a series of laterally directed upwardly inclined burner ports 39. A burner grate 40, incorporating the features of the top grate 14 in the first described structure, is mounted on the cover plate 37. The burner grate in this modification comprises a top plate member 41 having a plurality of feet 42 adapted to support the grate upon the burner plate 37 and is attached thereto by screws 43.

An annular burner guard 24, such as shown in the above described structure, may be provided under the periphery of the burner grate 40.

It should be pointed out that the cover plate 37 and the boss 42 may be made integral with each other, instead of separated, as shown.

The operation of the burner grate shown in Figs. 3, 4 and 5 is essentially the same as that shown in the previously described structure, and the advantages gained by the top grate 14 are likewise gained by the burner grate 40.

Many other embodiments of the invention may be resorted to without departing from the spirit of the invention.

I claim:

1. A gas range device of the class described, comprising: a range top sheet having a burner-receiving opening, the margins of said opening at first curving upwardly from the normal level of the top sheet to form a raised outer rim and then curving downwardly and terminating in an upturned inner rim depressed below the normal level of said range top sheet; a burner structure for said opening including an annular outer main burner and an inner simmer burner; and a utensil-supporting grate plate in the form of a flat unperforated disk carried by said burner structure and extending radially beyond said main burner and over the depressed margins of said opening in spaced relation therewith and into contiguous relation with said upraised outer rim to define therewith an uninterrupted annular outlet.

2. A gas range device of the class described,

comprising: a range top sheet having a plurality of burner receiving openings, each bordered by an upwardly curved rim; an annular burner guard including an upwardly curved outer margin conforming to the marginal rim of said opening and a depressed channel bordering its inner margin and forming an upturned inner rim above said channel but below the normal surface of said top sheet; a burner unit for each burner opening, 5 said burner unit including an annular main burner projecting above the inner rim of said burner guard and having radially directed burner orifices, an inner simmer burner projecting above said main burner and having radially directed burner orifices, the burner orifices of said main and simmer burner being between the planes defined by the upwardly curved outer marginal portion and upturned inner rim of said burner guard; and a utensil-supporting grate plate in 10 the form of a flat disk carried by said burner structure, said plate projecting radially beyond said main burner and positioned above said burner guard, and terminating in spaced relation with the outer margin of said burner guard to 15 form an uninterrupted annular discharge opening for the products of combustion.

3. A gas range device of the class described, comprising: a range top sheet having a plurality of burner receiving openings, each bordered by an upwardly curved rim; an annular burner guard having an outer margin conforming to the margin of said opening and a depressed inner rim 20 depressed below the outer rim and defining an upwardly facing channel; a burner unit for each burner opening, said burner unit including an annular main burner projecting above the inner rim of said burner guard and having radially directed burner orifices, an inner simmer burner projecting above said main burner and 25 having radially directed burner orifices, the burner orifices of said main and simmer burner being between the planes defined by the upwardly curved outer marginal portion and upturned inner rim of said burner guard; and a utensil-supporting grate plate in the form of a flat disk carried by said burner structure, said plate projecting radially beyond said main burner and positioned above said burner guard, and terminating in spaced relation with the outer margin of said burner guard to form an uninterrupted annular discharge opening for the products of combustion.

4. A gas range structure comprising: a main burner of annular form having radially directed 30 burner ports; a simmer burner extending upwardly through and spaced from the main burner, said simmer burner having radially directed burner ports located above the upper end of the main burner; an imperforate grate plate 35 mounted on said simmer burner and extending over and beyond the outer periphery of said main burner in spaced relation therewith; an annular burner guard ring surrounding said main burner and spaced from said main burner and grate plate to define therewith a combustion zone; said guard ring having an upturned inner marginal rim disposed below the ports of said main burner, and an upturned outer marginal rim disposed above the level of said main burner ports and 40 radially outward of the periphery of said grate plate.

5. A gas range structure comprising: a main burner of annular form having radially directed 45 burner ports; a simmer burner of relatively small diameter extending upwardly through the an-

nulus formed by the main burner and spaced from the walls thereof to define therewith an annular air passage, said simmer burner having ports directed radially outwardly over said main burner; an imperforate grate plate supported by said simmer burner and extending over and beyond the main burner in spaced relation therewith, thereby to define with the main burner a radially directed combustion zone for said simmer burner and ignition passage through which an ignition flame may travel between said burners; an annular burner guard ring surrounding said main burner and spaced from said main burner and grate plate to define therewith a combustion zone; said guard ring having an upturned inner marginal rim disposed below the ports of said main burner, and an upturned outer marginal rim disposed above the level of said main burner ports and radially outward of the periphery of said grate plate.

6. A gas range device as set forth in claim 1, wherein: said simmer burner projects above the outer burner unit and is provided with outwardly directed burner jets; and said utensil-supporting grate plate is carried by said simmer burner.

7. A gas range device as set forth in claim 1, wherein: said simmer burner is disposed below the upper extremity of the main burner; and said

utensil-supporting grate plate is carried by said main burner and defines therewith lateral apertures for escape of the products of combustion from said simmer burner.
